Primary Examiner — Clare E Heflin(74) *Attorney, Agent, or Firm* — Koppel, Patrick, Heybl & Philpott(57) **CLAIM**

The ornamental design for a pole mount light, as shown and described herein.

DESCRIPTION

FIG. 1 is a perspective view of a pole mount light according to an embodiment of the present invention.

FIG. 2 is a front elevation view of a pole mount light according to an embodiment of the present invention.

FIG. 3 is a rear elevation view of a pole mount light according to an embodiment of the present invention.

FIG. 4 is a side elevation view of a pole mount light according to an embodiment of the present invention.

FIG. 5 is a top plan view of a pole mount light according to an embodiment of the present invention; and,

FIG. 6 is a bottom plan view of a pole mount light according to an embodiment of the present invention.

The broken lines shown on the drawings depict environmental subject matter only and form no part of the claimed design.

1 Claim, 3 Drawing Sheets(56)
